UNITED STATES PATENT OFFICE.

JAMES H. RAND AND JAMES H. RAND, JR., OF NORTH TONAWANDA, NEW YORK

ADJUSTABLE INDICATOR.

1,106,843.

Specification of Letters Patent.

Patented Aug. 11, 1914.

Application filed April 29, 1914. Serial No. 835,088.

To all whom it may concern:

Be it known that we, JAMES H. RAND and JAMES H. RAND, Jr., citizens of the United States, and residents of North Tonawanda, in the county of Niagara and State of New York, have invented new and useful Improvements in Adjustable Indicators, of which the following is a specification.

This invention relates to adjustable indicators or indexes, and consists in the novel and improved structure hereinafter set forth, by which the removable and adjustable indicator strips are prevented from slipping over one another or piling up when mounted in the frame, especially when shifted several at a time up or down in the frame, and by which the strips are also locked individually in the frame against accidental dislodgment.

In the accompanying drawings which illustrate certain embodiments of the invention,—Figure 1 is a face view of part of an indicator or index containing the invention; Fig. 2 is a perspective view of one of the indicator strips; Fig. 3 is a cross sectional view 25 of the indicator shown in Fig. 1; and Figs. 4, 5 and 6 are cross sectional views of other forms of indicators containing the invention.

Referring first to Figs. 1, 2 and 3, A represents the frame of the indicator, which may 30 be made of tin or other sheet metal, and is provided with flanges B, one at each side, forming inwardly facing guide channels for engaging the ends of the indicator strips. A pair of lengthwise extending ribs C are 35 struck up from the back of the frame, between and parallel to said guide channels, as shown.

The indicator strips or cards, formed of bristol board or other suitable material, are 40 shown at D. Each indicator strip D is folded or bent over upon itself at each end, and the folded portions are held within said guide channels, which are of such height as to receive the double thickness of the strips 45 formed by the fold, with only sufficient clearance to allow the strips to slide up and down freely in the frame for the purpose of adjustment. The length of each fold d is such that it will make a reasonably close fit between the guide channel and the nearer of the two ribs C, C, which furnish shoulders against which the ends of the folds d abut.

When inserting a strip into the frame, the strip is buckled or shortened a little lengthwise, and the folded ends inserted under

the guide flange B, whereupon the strip will again spring out flat into normal position with both ends held in the guide channels. When the strip thus assumes its normal position, the ends of the folds d drop behind the 60 ribs or shoulders C, and lock the strips against accidental dislodgment from the frame. The fit of the folds d between the channels and the ribs is sufficiently free, however, so as not to bind, or interfere with 65 the movement of the strips, one or many at a time, up and down in the frame. It will also be possible with this construction to remove the strips from the frame without damaging the strips, by using due care, but 70 as the strips are commonly used for listing names, etc., and as they are rarely used after they are once removed, they may ordinarily be pulled out without regard to breaking or 75 damaging the folds d which abut against the ribs C. It will be clear that the process of inserting the strips into the frame in no way endangers the strips or the folds d.

In Fig. 4 the shoulders or ribs C', C', are formed by bending or striking up a single 80 broad section of the back of the frame instead of two separate narrow ridges as in Fig. 3. In Fig. 5, which illustrates a double faced indicator, the shoulders or ribs C², C², are formed of separate folded strips of sheet 85 metal secured to the back of the frame. In other respects the construction and operation of the devices shown in Figs. 4 and 5 are substantially the same as in Figs. 1 and 3.

In Fig. 6, the frame and the indicator strips are the same as already described excepting that no lengthwise extending ribs or shoulders are provided against which the ends of the folds d abut. In this form the advantages of the double thickness of the strips at their ends, are attained in preventing the cards from slipping over one another or piling up, when several strips of the series are shifted up or down together; but the other feature of locking the strips individually in the frame is, of course, lacking.

We claim:

1. An adjustable indicator comprising a frame having flanges forming inwardly facing guide channels, and a series of indicator strips each of which is folded over upon itself at both ends, the folded portions being removably held in said guide channels and co-operating with said flanges to prevent said strips from slipping over one another. 110

2. An adjustable indicator comprising a frame having flanges forming inwardly facing guide channels and also having a pair of lengthwise extending ribs arranged between and parallel to said guide channels, and a series of indicator strips each of which is folded back upon itself at both ends, the folded portions being held in said guide channels, and said lengthwise extending ribs

coöperating with the ends of the folds of the strips to lock the strips in the frame.

Signed at North Tonawanda, New York,
this 24th day of April, 1914.

JAMES H. RAND.
